UNITED STATES PATENT OFFICE

2,051,007

REVOLVING DOOR

Edmund Peremi, Manhasset, and Charles Kish,
Elmhurst, N. Y., assignors to General Bronze
Corporation, Long Island City, N. Y., a corpo-
ration of New York

Application April 20, 1935, Serial No. 17,378

15 Claims. (Cl. 20—18)

This invention relates to revolving doors and more particularly to revolving doors of the so-called panic-proof type.

In panic-proof doors the leaves are normally held radially disposed, but are adapted to yield under a predetermined pressure to a collapsed condition when panicky persons rush heedlessly against the door leaves. The leaves are also adapted to be collapsed when it is desired to clear the doorway for permitting merchandise to be carried into or out of the building. For the latter purpose provision is made to relieve or relax the force normally tending to hold the leaves in radial position so that they may be collapsed without undue exertion.

One feature of the present invention has to do with detent mechanism for the above-indicated purpose, and as to this feature the invention is in the nature of an improvement upon the invention disclosed and claimed in United States Letters Patent No. 1,983,395, granted to Edmund Peremi and Charles Kish on December 4, 1934.

In accordance with this feature provision is made of means for applying spring pressure to the detent mechanism and of a key operated device for shifting said pressure applying means between fully effective and relaxed positions, it being a point of the present invention that the key operated device is locked or latched in position to maintain the maximum pressure, so that there is no liability of less than the maximum pressure being normally applied through accidental or careless setting of the pressure applying means.

In accordance with a further feature provision is made of simplified means for changing the normal adjustment of the device to secure a selected normal or maximum pressure.

A further feature of the invention has to do with releasable chain mechanism for normally connecting the leaves to one another. Either the chain mechanism may be used or the detent mechanism may be used to the exclusion of the other, but they are desirably used jointly as illustrated herein.

It is a feature of the invention that one end of a chain is yieldingly retained between a rocker and a manually operable trigger or latch, the trigger being adapted to be operated manually to release the chain by the exertion of a slight force, and the rocker being adapted to yield to release the chain in response to separating force exerted upon adjacent leaves. The rocker opposes substantial resistance to the release of the chain and may be employed to supplement the force exerted by the detent.

It is a feature that the rocker is held in normal position by spring pressure and that provision is made of means for adjusting the spring pressure acting to retain the rocker in normal position at will.

A further feature of the invention has to do with the provision of a chain terminal block located within a leaf and normally locked in fixed position, together with adjustable means operable from the exterior of a leaf for releasing, readjusting and relocking the lock. Other objects and advantages will hereinafter appear.

In the drawings forming part of this specification,

Figure 1 is a sectional plan view illustrating a revolving door embodying features of the present invention;

Figure 2 is a view in sectional elevation of the door of Fig. 1;

Figure 3 is a fragmentary, sectional, horizontal view showing the door leaves and the mounting thereof upon the central shaft or spindle;

Figure 4 is a fragmentary, vertical, sectional view illustrating the detent mechanism and parts associated therewith;

Figure 5 is a fragmentary, sectional bottom plan view illustrating the detent mechanism and associated parts;

Figure 6 is a fragmentary view in elevation illustrating the exterior of the device for changing the pressure upon the detent.

Figure 7 is a sectional detail view taken on the line 7—7 of Fig. 4 looking in the direction of the arrows;

Figure 8 is a fragmentary sectional view in elevation taken upon the line 8—8 of Fig. 9 looking in the direction of the arrows;

Figure 9 is a fragmentary view in elevation illustrating features of the chain connecting mechanism;

Figure 10 is a fragmentary, horizontal, sectional view taken upon the line 10—10 of Fig. 9 looking in the direction of the arrows; and

Figure 11 is a fragmentary horizontal, sectional view taken upon the line 11—11 of Fig. 9 looking in the direction of the arrows.

The door 1 comprises a series of leaves 2 which are mounted upon a rotary central support 3 to turn within a doorway having arcuate walls 4. The central rotary support includes a vertical shaft 5 which extends through the ceiling of the doorway and is revolvably suspended from a trolley (not shown). This trolley is movable upon a track (not shown) to move the folded leaves to one side of the doorway when the

leaves have been collapsed. The vertical shaft 5 has fixed upon it a pair of discs 6, one located near the lower end of the shaft, and the other near the upper end thereof. Each of the discs 5 is formed to interact with cooperating elements on the leaves for supporting the leaves, for normally retaining the leaves in radial position, and for guiding the folding movements thereof. The leaf carried members are mounted in a hanger 7 which comprises complementary housing plates 8 and 9.

The details of the discs 6 and the members co-acting therewith for controlling the paths of the leaves in collapsing is the same as that disclosed in the Patent No. 1,983,395, referred to above, and will not be described in detail.

The detent mechanism employed in each leaf for coacting with the disc may be the same in its interaction with the disc as the corresponding mechanism disclosed in said patent.

Each detent comprises angularly related arms 10 and 11 which are pivoted at their outer ends upon a slide 12. A light spring 13 is mounted in a slot 14 of the slide 12 and bears against a fixed lug 15 for thrusting the slide 12 toward the disc 6. The arms 10 and 11 normally engage in notches 16 and 17 of the disc to hold the leaf in radial position. The pressure exerted by the spring 13 is very light, however, and its force is supplemented by the force of a spring 18 applied through a lever 19 pivoted on a shaft 20.

The spring 18 is mounted in a bore 21 formed in a rack 22, and is provided with a cap 23 slidable in the bore 21. The cap 23 bears against the upper side of the lever 19 and normally holds the outer end of said lever down against a fixed abutment 24. The rack is operable to move the spring 18 toward and away from the fulcrum 20 of the lever 19 and hence to diminish and increase the force with which the lever acts to thrust the slide 12 toward the disc 6. When the spring 18 is directly over the axis of shaft 20 the spring 18 becomes wholly ineffective and the slide is thrust inward solely by the light force of the spring 13. The door leaf may then be readily collapsed. When it is desired to again lock the leaf in normal position it is first swung to normal position to re-engage the detent arms 10 and 11 with the notches 16 and 17. The rack is then operated to move the spring 18 outward to its original position which may be the position illustrated in Fig. 4.

The rack is driven by a pinion 24 which has a hub portion 25 provided with a key socket 26. The key socket 26 is accessible from the exterior of the door so that an authorized person may operate the pinion merely by inserting a key and performing the required manipulation. The pinion at the side opposite the hub 25 has a bearing pin 27 received in a bore 28 of the plate 8. A metallic bow spring 29 is interposed between the pinion and the plate 8. The bearing pin 27 is made short enough to have substantial endwise play in the bore 28 so that the pinion can be thrust axially by the operator against the force of the spring 29.

The hub portion 25 is journaled in an annular flange 30 formed on a plate 31, and the plate 31 is secured to the plate 8 by screws 32. The flange 30 is provided with a stop shoulder 33 for limiting the operation of the pinion in the direction to move the spring 18 outward, the stop shoulder being effective definitely to control and determine the maximum force which

the spring 18 can apply to the slide 12. This is the normal force resisting collapsing, and it is desirable that it be secured in every instance and that it be maintained at all times, except when an authorized person uses the key with the intention of collapsing the leaves.

The flange 30 is therefore provided with a locking notch 34 adjacent the shoulder 33 for receiving a pin 35 carried by the pinion to lock the pinion against operation. When the pinion 10 is turned to carry the pin 35 into register with the notch 34, the spring 29 acts automatically to thrust the pinion axially and thereby to snap the pin 35 into locked engagement with the notch 34. When the key is inserted, however, it may be pressed in to move the pinion axially a sufficient distance to cause the pin 35 to clear the notch 34, and the pinion may then be operated to move the spring 18 toward the fulcrum of lever 19.

Statutes and ordinances in various jurisdictions specify maximum limits of resistance to collapsing of the door leaves which may not be exceeded. These limits vary, however, for different jurisdictions, so that it is desirable to provide a construction in which the maximum resistance to collapsing may be adjusted to any one of a series of predetermined values. This is accomplished in a very simple and effective manner in accordance with this invention, by providing a series of screw holes in the plate 9 (with corresponding openings in the cover plate which overlies the plate 9) so that the screws 32 may be inserted in any selected pair of diametrically opposed screw holes. The selection of the screw holes determines the position of the stop shoulder 33, and hence the maximum or normal pressure which the spring 18 may apply to the slide 12.

The door leaves are desirably connected when in normal positions by chains 40, each chain being connected at one of its ends to one of two adjacent door leaves through an end block 43. The end block 43 has recesses 44 and 45 formed in the opposite faces thereof, the recesses forming a waist portion of 45 the block which is received between ears 46 and 47 which form parts, respectively, of a rocker 48 and a latch 49. The latch 49 is pivotally mounted upon a vertical pin 50 and is yieldingly urged in a clockwise direction (as seen in Fig. 10) by a compression spring 51. The spring 51 is interposed between a boss 52 forming part of a stationary plate 53 and an ear 54 formed on the latch. Screws 55 and 56 are threaded through the boss 52 and the ear 54, respectively, and have their ends received within the end turns of the spring 51 to hold the spring in place. The latch is provided with a handle portion 57 which projects outward a short distance beyond the face of the door through a slot 58 and normally bears against the end of the slot. When it is desired to release the chain manually the trigger is engaged by a finger of the operator and moved counterclockwise to a position clear of the recess 45. When this is done the chain can be readily withdrawn or may drop from the door leaf under the influence of its own weight.

The latch, however, cannot be turned counterclockwise from its normal position, and hence release of the chain, in response to separating force 70 exerted upon the connected leaves, can only result in a release of the chain through a displacement of the rocker 48.

The rocker 48 is pivotally mounted upon a vertical pin 59 and is normally held in engage- 75

ment with a plate 60 by a compression spring 61. The spring 61 encircles the shank of a screw 62 which is threaded through a nut 63 and which bears at its end remote from the head against a plate 64. The lower face of the head of the screw 62 engages the rocker 48. The nut 63 has a flat side disposed in engagement with a shoulder 65 and is prevented from turning by said shoulder. The head of the screw 62 has a rim 10 portion 66 which is received in an undercut recess 67 formed in the plate 60. Since the screw is just long enough to engage the opposite plate 64 when its rim 66 engages the wall of the recess 67, it is not possible to turn the screw accidentally completely out of the nut 63, and hence the operative relation of the parts cannot be accidentally or maliciously disturbed. Rotation of the screw 62 is effective to move the nut 63 longitudinally of the screw, and hence to increase or 20 diminish the spring pressure which must be overcome in order to free the block 43 by displacement of the rocker 48 from normal position.

Each chain is secured at its opposite end to an adjacent door leaf through an end link 68 which extends into the leaf through slots formed in successive plate or block members 64, 69, 70 and 71. The plate 71 is serrated and interfits with the serrated face of a block 72 located within the door. The end link 68 fits into and 30 extends through a boss 73 formed on the block 72. A coiled spring 74 is received in a bore 75 formed on the block 72. A coiled spring 74 is received in a bore 75 formed in the boss 73 and bears against the base of the bore outside the 35 bounds of the end link 68. A circular nut 76 is threaded onto the end of the link 68 and bears against the spring 74, being itself of small enough diameter to be received in the bore 75. The spring 74 provides a certain amount of yielding 40 for the chain, and at the same time prevents the occurrence of objectionable slack.

Provision is made for adjusting the block 72 relative to the plate 71 and for locking it in 45 adjusted position from the exterior of the door leaf. A screw 77, having a collar portion 78 disposed against the inner face of the plate 64, has a threaded shank 79 which extends through an elongated slot 80 in the block 72, and a reduced end portion 81 which has bearing in a bore 82 of the block 53. A nut 83 is threaded on the shank 79 of the screw and has flat sides which 50 fit between the walls of the slot 80. The nut 83 also has wings or ears 84 which overlie the block 72 and extend outward beyond the sides of the slot 80. The screw is normally turned to draw 55 the ears 84 firmly against the block 72 to hold the block 72 clamped in interlocking relation with the plate 71. When it is desired to adjust the block 72 to a different position, the screw 77 is turned in a direction to back the nut 83 away 60 from the block 72. This leaves the block 72 free to be readjusted and it may be moved to the new desired position by seizing and moving the end link 68 through which the chain is connected to the block. The block 72 may then be locked in its new position by turning the screw 77 in a direction to draw the nut 83 toward the head of the screw so as to cause the ears 84 to clamp the block 72 against the plate 71.

While we have illustrated and described in detail certain preferred forms of our invention, it is to be understood that changes may be made therein and the invention embodied in other structures. We do not, therefore, desire to limit 70 ourselves to the specific constructions illustrated,

but intend to cover our invention broadly in whatever form its principle may be utilized.

We claim:

1. In a revolving door, the combination with a central rotary support and leaves collapsibly mounted thereon, of a detent carried by each leaf, means for yieldingly applying holding pressure to each detent to hold the leaf yieldingly in normal position, said pressure applying means being operable between effective and relatively ineffective positions, an operating device for the pressure applying means and means automatically locking the operating device against undesired operation.

2. In a revolving door, the combination with a central rotary support and leaves collapsibly mounted thereon, of a detent carried by each leaf, means for yieldingly applying holding pressure to each detent to hold the leaf yieldingly in normal position, said pressure applying means being operable between effective and relatively ineffective positions, an operating device for the pressure applying means and means for latching the operating device to cause it positively to retain the pressure applying means in effective position.

3. In a revolving door, the combination with a central rotary support and leaves collapsibly mounted thereon, of a detent carried by each leaf, means for yieldingly applying holding pressure to each detent to hold the leaf yieldingly in normal position, said pressure applying means being operable between effective and ineffective positions, an operating device for the pressure applying means and means for latching the operating device to cause it to retain the pressure applying means in effective position comprising a rotatable and axially movable pinion, a projection carried by the pinion, a notched member alongside the pinion and a spring automatically effective when the projection is aligned with the notch to move the pinion axially to engage the projection in the notch.

4. In a revolving door, the combination with a central rotary support and leaves collapsibly mounted thereon, of a detent carried by each leaf, means for yieldingly applying holding pressure to each detent to hold the leaf yieldingly in normal position, said pressure applying means being operable between effective and ineffective positions, an operating device for the pressure applying means and means for latching the operating device to cause it to retain the pressure applying means in effective position, comprising a rotatable and axially movable pinion, a locking member alongside the pinion, said pinion and locking member having interfitting latching portions and a spring automatically effective when the interfitting portions are aligned by rotation of the pinion to move the pinion axially to snap said portions into interfitting engagement.

5. In a revolving door, the combination with a central rotary support and leaves collapsibly mounted thereon, of a detent carried by each leaf, means for yieldingly applying holding pressure to each detent to hold the leaf yieldingly in normal position, said pressure applying means being operable between effective and ineffective positions, an operating device for the pressure applying means and means for latching the operating device to cause it to retain the pressure applying means in effective position comprising a rotatable and axially movable pinion, a locking member alongside the pinion, said pinion and locking member having interfitting latching por-

- tions and a spring automatically effective when the interfitting portions are aligned by rotation of the pinion to move the pinion axially to snap said portions into interfitting engagement, said locking member being mounted co-axially with the pinion, and means for facilitating the mounting of the locking member in different angular positions about the pinion axes.
6. In a revolving door, the combination with a central rotary support and leaves collapsibly mounted thereon, of a detent carried by each leaf, means for yieldingly applying holding pressure to each detent to hold the leaf yieldingly in normal position, said pressure applying means being operable between effective and ineffective positions, an operating device for the pressure applying means and means for latching the operating device to cause it to retain the pressure applying means in effective position comprising a rotatable and axially movable pinion, a locking member alongside the pinion, said pinion and locking member having interfitting latching portions and a spring automatically effective when the interfitting portions are aligned by rotation of the pinion to move the pinion axially to snap said portions into interfitting engagement, said pinion having a hub portion journaled in the locking member and provided with a key socket which is exposed through the locking member, whereby the pinion may be first moved axially by key pressure to unlock it and then turned by rotation of the key.
7. In a revolving door, the combination with a central rotary support and leaves collapsibly mounted thereon, of chains connecting adjacent leaves, and means connecting a chain to a leaf comprising an end block on the chain, a rocker normally interfitted with the end block, and holding the same against release, a spring urging the rocker to normal locking position, a stationary abutment within the leaf for sustaining the spring, means extending transversely of the leaf and operable from the exterior of the leaf to adjust the abutment toward and from the normal position of the rocker to change the force required to be overcome in order to release the chain, and means preventing removal of the adjusting means from the leaf.
8. In a revolving door, the combination with a central rotary support and leaves collapsibly mounted thereon, of chains connecting the adjacent leaves and means connecting a chain to a leaf comprising an adjustable anchor block within the leaf, a supporting plate for the anchor block and a clamp operable from the exterior of the leaf to clamp the anchor block to the supporting plate and release the same at will.
9. In a revolving door, the combination with a central rotary support and leaves collapsibly mounted thereon, of chains connecting the adjacent leaves and means connecting a chain to a leaf comprising an adjustable anchor block within the leaf, a supporting plate for the anchor block, a clamp for holding the anchor block to the supporting plate, a screw passed through the block and plate and a nut threaded on the screw, said anchor block having a slot in which the nut is partially received and said nut having flat sides for engaging the walls of the slot and clamping wings extending outward beyond the bounds of the slot.
10. A structure as set forth in claim 9 wherein the anchor block and the supporting plate have complimentary serrated faces.
11. A structure as set forth in claim 9 wherein provision is made of means for permanently restraining the screw against endwise movement.
12. In a revolving door, the combination with a central rotary support and leaves collapsibly mounted thereon, of chains connecting the adjacent leaves and means connecting a chain to a leaf comprising an adjustable anchor block within the leaf, a supporting plate for the anchor block, said anchor block having a bore therethrough and said chain having an end link fitting in said bore.
13. In a revolving door, the combination with a central rotary support and leaves collapsibly mounted thereon, of chains connecting the adjacent leaves and means connecting a chain to a leaf comprising an adjustable anchor block within the leaf, a supporting plate for the anchor block, said anchor block having a bore therethrough and said chain having an end link fitting in said bore, a spring surrounding the end link and bearing against said anchor block and a nut on the end link for engaging the spring in opposition to the anchor block.
14. In a revolving door, the combination with a central rotary support and leaves collapsibly mounted thereon, of chains connecting adjacent leaves, and means connecting a chain to a leaf, comprising an end block on the chain, a rocker normally interfitted with the end block and holding the same against release, a spring urging the rocker to normal locking position, a stationary abutment within the leaf for sustaining the spring, and means operable from the exterior of the leaf to adjust the abutment toward and from the normal position of the rocker to change the force required to be overcome in order to release the chain, the same, the abutment consisting of a nut held against rotation and the abutment adjusting means consisting of a screw threaded through the nut.
15. A structure as set forth in claim 14 wherein provision is made of means engaging the screw at opposite ends to hold it against endwise movement and to prevent its being turned with the nut.

EDMUND PEREMI. 60
CHARLES KISH.
